(57) **CLAIM**

We claim the ornamental design for a payload release hook, as shown and described.

DESCRIPTION

FIG. 1 is a front perspective view of an embodiment of a payload release hook showing our new design;

FIG. 2 is a rear perspective view thereof;

FIG. 3 is a front view thereof;

FIG. 4 is a rear view thereof;

FIG. 5 is a cross-sectional view thereof taken from section 5-5 in FIG. 3;

FIG. 6 is a right side view thereof (the left side is a mirror image of the right side);

FIG. 7 is a top view thereof;

FIG. 8 is a bottom view thereof;

FIG. 9 a front perspective view of the cross-section shown in FIG. 5; and,

FIG. 10 is a rear perspective view of the cross-section shown in FIG. 5.
